(57) **CLAIM**

The ornamental design for a rocker panel, as shown and described.

DESCRIPTION

FIG. 1 is a perspective view of the rocker panel of the present invention, understanding that mirror views of these views are possible;

FIG. 2 is a front elevation thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The broken lines illustrate the design's environment and form no part of the claimed design.
